UNITED STATES PATENT OFFICE.

OTTO A. HEPPE, OF CHICAGO, ILLINOIS, AND CHESTER E. RAHR, OF BROOKLINE,
MASSACHUSETTS.

PROCESS OF MAKING PREPARED ROOFING AND APPARATUS USED IN CONNECTION THEREWITH.

1,392,498.

Specification of Letters Patent.

Patented Oct. 4, 1921.

Application filed December 5, 1918. Serial No. 265,346.

To all whom it may concern:

Be it known that we, OTTO A. HEPPE and CHESTER E. RAHR, both citizens of the United States, residing, respectively, in the 5 city of Chicago, county of Cook, and State of Illinois, and the city of Brookline, county of Suffolk, and State of Massachusetts, have invented certain new and useful Improvements 10 in Processes of Making Prepared Roofing and Apparatus Used in Connection Therewith, of which the following is a specification.

This invention relates to improvements 15 in a process of making prepared roofing and apparatus used in connection therewith and refers more particularly to a process and apparatus for economically saturating, coating and cooling prepared roofing.

The object of the invention is to provide 20 a process and apparatus in which material passes over the saturating tank to the coating tank and thence to the cooling rolls in such a manner as to take advantage of gravity action and thereby lessen tendency 25 to tear the roofing.

In the drawing, is shown a somewhat dia- 30 grammatic view of the novel form of apparatus used to carry out the invention.

Referring to the drawing, *a*, *b*, *c*, and *d* 35 designate the various floors of a roofing plant or various heating zones of successively decreasing temperature, the hottest zone being at the top. It is not necessary that these heating zones be on separate floors but this is merely a convenient manner of arrangement. In the room or zone *a*, is mounted the saturating tank 1, provided with usual rolls 2 over which is fed the 40 roofing length or fabric 3 from the drum 4. After the roofing length 3 leaves the saturating tank 1, it passes over rolls 5 and 6 and thence down through a suitable opening 7 in the chamber *a* to the roll 8 in the chamber 45 *b*. The roofing length then passes between the spreader or pressure rolls 9 mounted above a tank 10. The roofing length is here coated by the coating material which can be passed through the spout or nozzle 11 50 connected to a suitable source of supply not shown. After being coated, the roofing passes beneath the hopper 12 containing the granular facing of the desired character

and thence through the rolls 13. The ex- 55 cess roofing drops into the box 14 and the granular coated roofing now passes between rolls 15 and 16 where, if desired, talc may be applied through the hopper 17 to the other side of the roofing. The length of roofing now passes out of zone *b* through 60 suitable opening 18 in the floor into the zone *c*. There the roofing passes over cooling idler rolls 19 and thence through opening 20 into the zone *b* where it is wound up 65 on drum 21.

Of course the step of putting on the granular facing may be omitted if desired or may be at a different place in the travel 70 of the roofing length. Similarly the step of putting on the talc to the under facing of the roofing to prevent sticking may be omitted. By the arrangement just described, the roofing can be much more quickly cooled and fed forward much more economically 75 than in present practice.

The invention is not limited to the de- 80 tails of construction or operation shown except as set forth in the appended claims.

We claim as our invention:

1. A process of making prepared roofing 85 consisting in passing the roofing fabric through a saturating tank seated in a heated zone, thence passing the saturated roofing fabric downwardly into a zone of lesser heat than the first and there coating the same, thence passing the roofing still farther downwardly into a still cooler zone and causing 90 it to pass therethrough a sufficient length of time to cool it and finally collecting the cooled saturated and coated roofing.

2. In an apparatus of the character de- 95 scribed, the combination with a saturating tank, located in a suitable chamber, means for feeding the roofing length through said tank, means for coating the saturated roofing length located in a chamber situated below the first chamber, means for cooling the saturated and coated roofing, comprising a plurality of rolls located in a chamber be- 100 low the second chamber and means for collecting the completed roofing.

3. A process of making a prepared roofing 105 consisting in passing the roofing fabric through a substantially horizontal saturat- ing tank, thence passing it downwardly to

coating mechanism where it is coated and thence passing the roofing downwardly and substantially vertically over cooling rolls and finally winding it up.

- 5 4. A process of making prepared roofing consisting in passing it through a saturating tank located in a compartment constituting the hottest zone, thence passing it to

a second compartment to lesser heat where it is coated, thence passing it to a third compartment of still cooler temperature where it is cooled thence to a final compartment where the product is collected. 10
